UNITED STATES PATENT OFFICE.

JOHN W. SCHOELLNER, OF NEWARK, NEW JERSEY, ASSIGNOR TO SCHOELLNER & HOR-BACH MFG. CO., OF NEWARK, NEW JERSEY, A CORPORATION OF NEW JERSEY.

SHIRT STUD.

Application filed September 27, 1921. Serial No. 503,593.

To all whom it may concern:

Be it known that I, JOHN W. SCHOELLNER, a citizen of the United States, residing at Newark, in the county of Essex and State 5 of New Jersey, have invented certain new and useful Improvements in Shirt Studs, of which the following is a specification.

This invention relates generally to a method of reinforcing metal parts and also 10 to an article of jewelry in the forming of which the method is employed.

In the manufacture of an article of jewelry in the form of a removable stud or fastener for clothing, an elongated base member is 15 made use of which normally assumes a position with the stem and button portion of the device located substantially midway between the extremities of the base member, provision being made for moving 20 the button along the base member to a point adjacent an end thereof to facilitate the placing of the device in, or its removal from, a button-hole. In order to provide for the automatic centering of the 25 button between the ends of the elongated base member a spring member is made use of and the base and base-engaging portions of the button take the form of hollow stems one of which encloses and slides on the 30 other, the spring being enclosed or housed within the hollow stems. This invention includes a method for forming an improved reinforced head on one of the relatively minute hollow stems in order to provide for 35 the forcing of the stem without collapse through a starched and resistant button-hole and to correspondingly stiffen and strengthen the entire base member. Other features 40 of the invention will be hereinafter referred to.

In the drawing,—

Figure 1 is a longitudinal section, partly broken away of a fastening device containing an embodiment of the invention.

45 Figure 2 is a sectional view in disassembled relation to the parts which are to be formed into a reinforced terminal member.

Figure 3 is a view similar to Figure 2 showing the parts assembled and subjected 50 to one step in a head-forming operation.

Figure 4 is a view similar to Figure 3 showing the parts subjected to another and final forming operation.

Figure 5 is an end view looking at the interior of a conical terminal member shown 55 in Figures 2 and 3.

Figure 6 is a side elevation of a portion of a hollow stem before attaching the terminal member thereto.

Figure 7 is a cross-section of the hollow 60 stem member shown in Figure 6 taken on the line 7—7.

Referring to the drawing, a shirt stud or fastener is shown in Figure 1 which includes the button member or top 5, a hollow stem 7 attached to the back of the top member 5, and an elongated base member 9 whose function it is to anchor the device in the button-hole in a well-known manner.

It will be seen that the elongated base 70 member 9 extends substantially at right angles to the button stem 7 and that the button top 5, in the normal position of the parts shown in Figure 1, occupies a position substantially midway between the ends of 75 the elongated base or anchoring member 9.

In order to move the button top 5 to a position adjacent one end of the base 9, the base member is made up of a hollow stem member 11 which is mounted to slide 80 longitudinally in a laterally diverted extension 13 of the button stem 7. A helical spring 15 of the expansion type is held in a compressed condition within the hollow stem 11 and bears at one end against the 85 closed right-hand end 17 of the stem 11 in Figure 1 and at the other end against a seat 19 in the form of a tongue of metal cut in the wall of the stem 13 and bent inwardly at an angle to the axis of the stem to operate in a longitudinally extending slot 20 in the stem. It will thus be seen that the spring presses against the closed end 17 of the stem 11 and tends to press the stem 11 to the right, in Figure 1, and against the 90 tongue or seat 19 on the stem 13 thereby tending to press the stem 13 and button 5 to the left.

It will be seen that the button 5 and stem 7 can be moved to the right along the stem 100 11 and against the pressure of the spring 15 until the button stem 7 is stopped by engagement with a stop lug 21 formed at the upper right-hand extremity of the stem 11, to facilitate the passing of the right-hand 105 end of the stem 11 through the button-hole.

This operation is assisted by the angular or beveled formation of the stem-end 17, as will be clear.

In order to reinforce the opposite end of the stem 11 and also to make it possible to force this end through a button-hole closed and stiffened with starch, a pointed head or terminal member 23 is provided for the stem 11. The terminal member 23 also acts as a shoulder or stop which is engaged by the corresponding end of the stem 13 in the position shown in Figure 1 and which accordingly limits the relative movement of the stem 13 to the left.

15 The head or terminal member 23 is attached to the forked end of the stem 11 which is formed by the slot 20 in the following manner: A head core member 25, which may be spherical in form, is forced between the extremities of the separated portions or extensions 27 into which the slot 20 divides the stem, the stem extensions 27 being suitably anchored for the purpose. This operative step produces an upsetting or spreading 25 of the extreme ends of the stem extensions, to form seats 29 fitted to the engaged contour of the core 25, as will be clear.

The next step in the operation consists in compressing the flaring end of the hollow 30 conical head member 23 into encompassing and rigid engagement with the outer faces of the core-receiving seats 29 on the stem extension members to thereby bind the engaged parts into a rigid unitary terminal member. The terminal thus provided for the longitudinally split end of the hollow stem is capable of penetrating a resisting buttonhole without collapse and at the same time acts as a rigid reinforcement for the 40 split end of the tube as a whole.

It will be clear that the two steps for forming the head can be provided in two separate operations or in successive stages of a single forming operation as may be 45 found most convenient, and that by either process an exceedingly simple, efficient, and readily formed reinforced terminal for the hollow stem is provided.

What is claimed is:

50 1. The method of forming a terminal for an elongated member having spaced apart lateral walls which consists in forcing a terminal core member between the ends of said walls to spread the ends of the walls 55 apart, and in clamping a terminal shell about the core member and the spread-apart ends of the walls of the elongated member.

60 2. The method of forming a terminal for an elongated button anchoring member having a longitudinally divided end, which consists in bending the extreme ends of the divided portion outwardly away from each

other by inwardly forcing a core member against said ends to form a seat, and in clamping a metal shell in enclosing relation to said core member and the outwardly bent extremities of the anchoring member.

65 3. The method of forming a perforating terminal for a tubular member which consists in forcing a terminal core member against and into an end of the tubular member to spread apart the walls of the end of the tubular member to form a seat for the core, and in bending the flaring edge of a hollow substantially conical shell inwardly 70 to grip the core member and spread apart end of the tubular member.

75 4. The method of forming a reinforced perforating terminal head for a longitudinally split tubular member, having spaced apart walls, which consists in forcing between the ends of the walls a core member having a greater width than the width of the space between the walls to thereby spread 80 apart the ends of the walls and form a seat for the core member, and in bending the flaring edge of a conical shell into gripping relation with the spread apart ends of the walls of the tubular member and in enclosing 85 relation to the core member.

90 5. The method of forming a reinforced perforating head for a tubular member having a longitudinally split end which consists in forcing a substantially spherical core member against the end of the tubular member to force apart the walls and form a core-engaging seat, and in placing a hollow conical shell in enclosing relation to the core and compressing the flaring edge of the shell into locking engagement with the spread apart ends of the walls of the tubular member.

95 6. A fastener comprising a button having an elongated tubular base member, said base member being expanded at one end to form 100 a seat, a terminal core member mounted on said seat, and a terminally pointed shell enclosing within its base said core member and the expanded end of the tubular base member.

105 7. A fastener comprising a button having an elongated longitudinally divided base member, said button being movably mounted on said base member, the parts of said longitudinally divided base member being flared 110 on one end to form a seat, a spherical terminal core member engaging said seat, and a hollow pointed shell enclosing within its base portion said core member and the flared end of the base member.

115 In testimony whereof I affix my signature.

JOHN W. SCHOELLNER.
